UNITED STATES PATENT OFFICE.

CARL ZETTERLUND, OF CHICAGO, ILLINOIS.

CONTROLLING MEANS FOR HOISTING APPARATUS.

Application filed March 1, 1923. Serial No. 622,015.

To all whom it may concern:

Be it known that I, CARL ZETTERLUND, a citizen of the United States, residing at Chicago, in the county of Cook and State of Illinois, have invented certain new and useful Improvements in Controlling Means for Hoisting Apparatus, of which the following is a specification.

This invention relates, generally, to improvements in hoisting apparatus, but has particular relation to the controlling means for that type of such apparatus designed for use in building construction, for elevating material from a lower floor or point to an upper one, and for lowering material from an upper floor or point to a lower floor or point of a building, and it consists in certain peculiarities of the construction, novel arrangement and combination of the various parts thereof as will be hereinafter more fully set forth and specifically claimed.

The principal object of the invention is to provide an apparatus of the above mentioned general character, which shall be greatly simplified in its construction and operation over that of the machines or apparatus of the same class heretofore in general use, with its parts so made, arranged and co-operating with one another as to produce high efficiency, ease and rapidity in handling or moving material, yet in a most safe and secure manner.

Another object of the invention is to furnish a hoisting apparatus by means of which material can be raised to or lowered from a great height simultaneously, or if desired, can be raised to or lowered from intermediate points between the base and top of the apparatus.

Furthermore, the invention contemplates the provision and use of improved mechanism for controlling, clutching and releasing a pair of cable-winding drums whereby they will be caused to alternately elevate and lower a pair of elevators or cages of the apparatus, said operation being controlled at a point remote from said drums.

Other objects and advantages of the invention will become apparent from the following description and explanation. The invention will be explained and more readily understood when read in conjunction with the accompanying drawings, in which one embodiment of the invention is disclosed, it being obvious that changes and modifications may be resorted to without de-

parting from the spirit of the invention, so long as they come within the scope of the appended claims forming a part hereof.

In the drawings,—

Figure 1 is a plan view of a hoisting apparatus embodying the invention, illustrating the position of the parts when one of the elevators or carriers of the apparatus is in its raised position and the other one in its lowered position.

Fig. 2 is a side view in elevation, shortened for the convenience of illustration, and illustrating the parts in the same position as shown in Fig. 1.

Fig. 3 is a view partly in section and partly in elevation taken on line 3—3 of Fig. 2 looking in the direction indicated by the arrows, with the elevators of the apparatus in the same position as shown in Figs. 1 and 2.

Fig. 4 is a view partly in section and partly in elevation, taken on line 4—4 of Fig. 1 looking in the direction indicated by the arrows.

Fig. 5 is a plan sectional view taken on line 5—5 of Fig. 2, and

Fig. 6 is an enlarged sectional view of a portion of one of the combined cable-winding drums and clutch therefor of the apparatus, showing it mounted on a portion of the supporting shaft therefor.

Corresponding numerals of reference refer to like parts throughout the different views of the drawing.

The frame of the machine comprises a base 10 having near one of its ends spaced uprights 11 which are united at their upper ends by a cross-piece 12 and which uprights constitute the guide rails for the elevators or carriers of the apparatus, as well as afford support for certain members of the controlling means of the apparatus. The frame also includes an upright hollow pillow block 13 which is mounted on the base 10 near its end opposite the uprights 11, which block serves for the bearings of the drive shaft and main driven shaft of the apparatus, as well as a housing for the transmission gears which connect said shafts.

Transversely journaled on the block or housing 13 is a driven shaft 14 which has mounted thereon a gear 15 which is shown as being of the worm gear type, and which meshes with a worm 16 on that end of a power shaft 17 located in the housing 13 below the shaft 14 and at a right angle to said shaft. The power shaft 17 may be

driven by any suitable means not shown, and while I have shown the gearing for transmitting power from the shaft 17 to the shaft 14 as being of the worm and worm gear type, 5 yet it will be understood that I do not wish to be limited to such type of gearing, as any other suitable type may be employed.

Loosely mounted on the shaft 14 on each side of the block or housing 13 is a cable-winding drum 18 which are of similar construction and size. Each of these drums, see 10 Figs. 2 and 6, is provided with a hub 19, from which spokes 20 radiate and support at their outer ends an annulus or rim 21 which 15 extends laterally from each side of the spokes 20 and has at one of its edges a peripheral flange 22 and at its other edge a peripheral flange 23 provided with spaced teeth 24 to act as ratchet teeth for the purpose to be 20 presently explained. That part of the rim 21 of each of the drums adjacent the ratchet toothed flange 23, is provided with a plurality of spaced inwardly extended lugs 25, which are preferably equi-distantly spaced.

25 As is best shown in Figs. 5 and 6, each of the drums 18 is provided on one side only of the spokes 20, with a hub 19 and the hub 26 of the clutch is mounted on the shaft 14 and fixed thereto by means of a key 27 on 30 the opposite side of said spokes. A washer 28 is by preference interposed between each of the hubs 19 of each drum and the adjacent end of the hub 26 of the clutch, and surrounds the shaft, as is obvious. Extended 35 from each hub 26 is an arm 29 which terminates at its free end a short distance inwardly from the inner surfaces of the lugs 25 of each drum. Pivotally mounted near its outer end on one side of the arm 29 near 40 its outer end, is a clutch arm 30 which is provided around its pivot point with a flat faced hub 31 to provide an enlarged bearing against the arm 29 in order to prevent wabbling of the clutch arm 30 in the operation 45 of the device.

Mounted on the pivot of the arm 30 is a spring 32 which has one of its ends in engagement with the arm 30 and its other end connected to the arm 29 so as to retract said 50 arm after it has been drawn out of engagement with one of the lugs 25 by a means presently to be explained. Extended radially from the hub 31 of the clutch arm is a lug engaging arm 33 of such length that 55 when the clutch arm 30 is moved from the position shown by continuous lines to that shown by dotted lines in Fig. 6 of the drawing, its outer end will not contact with the inner surface of the flange of the drum but 60 will contact with one of the straight edged sides of one of the lugs 25 on the flange of the drum. Connected to the free end of each of the clutch arms 30 is one end of a cable 34, each of which engages a pulley 35 mounted on an upright 36 located near the outer

surfaces of the drums 18 and extends upwardly to a point near the upper end of the upright frame comprising the guide rails 11 for the elevators or cages.

Each of the cables 34 is secured at its 70 upper end to the front end of a lever 38. A pulley 37 journaled on a suitable bracket mounted on the upright frame work of the supporting frame near each of the upper corners thereof and above said lever has a cable extended thereon. Mounted on the upper portion of the rear surface and at each side of said upright frame work is a vertically disposed bracket 39, each of which has at its lower end a rearwardly extended 75 and apertured arm 40 and at a suitable distance above said arm with another rearwardly extended arm 41 each of which has an opening near its rear end for the reception of a pivot pin or fulcrum 42 for one of the levers 38 above mentioned. Each of the levers 38 has about midway between its ends an upright 43, each of which is provided with a laterally extended pin 44 to which one end of a spring 45 is secured the other 80 end of which is secured to the outer end of the arm 40 of each of the lever supporting brackets. It will be understood that the pivot 42 and securing points 40 and 43 for each of the springs 45 are so located with 85 respect to one another that when either lever 38 is depressed at its rear end, the line of tension of the spring actuating said lever will be rearwardly of its axis, thus holding the lever in its depressed position until its 90 rear end is manually elevated, when it will be understood that the line of tension of its spring will be forwardly of the lever fulcrum and will hold the front end of said lever in its depressed position. Each of the levers 38 has secured to its front end the 95 upper end of a cable 37 which pass over the pulleys 46 as above mentioned, and each is secured at its lower end to the upper portion of a safety dog 47 one of which is pivotally 100 mounted on the base 10 directly in the rear of the toothed flange 23 of each of the combined winding drums and clutches for engagement with the teeth of said flanges. Each of the dogs 47 is provided at its rear 105 lower portion with an extension 48 to contact with a portion 49 of the bracket 50 on which it is mounted for the purpose of preventing said dog assuming a position rearwardly of a vertical line through its axis, 110 yet permitting enough movement of the dog to allow it to be disengaged from the teeth of the ratchet with which it is adapted for engagement.

Mounted for vertical movement in each 115 of the guide-ways provided by the rails or uprights 11 is a cage or elevator generally designated by the numeral 51 which may be of any suitable type for conveying material and of such construction as to be guided 120

125

130

vertically by the rails of the upright frame work of the main frame. Journaled on the upper portion of said upright are a pair of sheaves 52, which are so located that their 5 rims will be positioned for movement in a vertical line extended through the middle of a transverse connection 53 with which each of the cages or elevators 51 is provided at its upper end.

10 Secured to the middle portion of each of the connections 53 of each of the cages is one end of a cable 54 which is extended over the pulleys 52 downwardly in front of the upright frame work of the main frame and 15 thence under a pair of pulleys 55 which are preferably swiveled on the lower portion of the upright or main frame.

As is clearly shown in Figs. 1 to 3 inclusive of the drawings, one reach of the cable 54 is wound around one of the drums 18 and the 20 other reach of said cable is wound around the other drum and said cable is extended around a pair of pulleys 56 mounted on the base 10 near and in front of the winding 25 drums, as is clearly shown in Fig. 1 of the drawings. By this arrangement it is evident that the winding drums on which the cable 54 is wrapped, will be so connected thereby to the elevators, that in the rotation of the 30 driven shaft 14 on which the drums are loosely mounted, until fixed to said shaft by means of the clutches carried by said drums, the elevators will be alternately raised and lowered and this operation can be controlled 35 by an operator stationed at the upper end of the upright frame work of the apparatus in order to reach and manipulate the levers 38 of the device.

In controlling the operation of the apparatus, it will be understood that by placing the levers 38 with their ends downwardly inclined, in which position the lever which controls the operation of the drum in front of the cage which is shown in its 45 lowered position, the clutches will be caused to engage the lugs 25 of each drum, by reason of the action of the springs 32 of said clutches. The forwardly inclined positions of the levers 38 will also hold the 50 safety dogs 47 out of engagement with their ratchets. In the elevation of either cage an upward extension 57 on the upper part thereof, will strike the forwardly inclined portion of its operating lever, thus moving 55 the front portion of said lever upwardly and permitting the spring 45 to hold said lever with its rear end in a downwardly inclined position as shown by one of the levers in Fig. 2 of the drawings. This 60 operation automatically throws the safety dog 47 in position to engage the ratchet on the drum in front of the cage which has been elevated and automatically throws and holds the clutch of said drum out of engagement 65 therewith.

As the clutch arms 30 are rotated by the driven shaft 14, it is manifest that in order to prevent the cables 34 which connect said clutch arms with the operating levers becoming twisted, said cables are secured to 70 the clutch arms so as to have a swivel action with respect thereto, and this may be accomplished by means of a knot 58 on the end of each cable adjacent the opening in the clutch arm through which it is extended. 75

Should it be desired to stop the elevators at points intermediate the top and bottom of the upright framework, it is apparent that the operating lever 38 which controls the clutch arm of the driving drum can be 80 manipulated so as to throw its clutch arm out of engagement with the lugs of said drum, at which time the safety lever 47 will be caused to automatically engage the peripheral rack of said drum and thus prevent 85 further movements of the elevators.

Having thus fully described my invention, what I claim as new and desire to secure by Letters Patent is—

1. An apparatus of the class described including in combination a main frame comprising a base and an upright frame-work thereon, said frame-work providing vertical guide-ways, a cage in each of said guide-ways for vertical movement, a spring actuated lever on each of said guide-ways, the spring of each lever acting thereon to alternately hold its ends in oppositely inclined positions, a driven shaft transversely journaled near one end of the base, means to 90 drive said shaft, a pair of drums loosely mounted on said shaft and each having inwardly extended lugs, a supporting arm keyed to the said driven shaft adjacent each drum, a spring actuated clutch arm pivotally mounted on each of said supporting arms, a connection uniting each of said clutch arms to one of said levers, and a cable co-operating with said drums and cages whereby the cages will be alternately raised 100 and lowered by the rotation of the driven shaft. 105

2. An apparatus of the class described including in combination a main frame comprising a base and an upright frame-work 115 thereon, said frame-work providing vertical guide-ways, a cage in each of said guide-ways for vertical movement, a spring actuated lever on each of said guide-ways, the spring of each lever acting thereon to alternately hold its ends in oppositely inclined positions, a driven shaft transversely journaled near one end of the base, means to drive said shaft, a pair of drums loosely mounted on said shaft and each having a 120 peripheral toothed rack, a safety dog pivotally mounted on said base to engage the rack of each drum, and a connection uniting each of said dogs to the front end of one of said levers. 125

3. In an apparatus of the class described, the combination with a main frame having an upright frame work providing guide-ways for a pair of elevators or cages, of an elevator or cage located in each of said guide-ways for vertical movement therein, a driven shaft transversely journaled on the main frame in front of said upright frame work, means to drive said shaft, a pair of drums loosely mounted on said driven shaft and each having a peripheral toothed rack and inwardly extended spaced lugs, a pair of pulleys journaled on the main frame in front of said drums, a pair of pulleys journaled on the upper portion of said upright frame work, a pair of pulleys journaled on the lower front portion of said frame work, a cable extended around the first named pair of pulleys and wound on each of said drums and extended therefrom around the pulleys at the lower portion of said frame work and over the pulleys at the top thereof and one reach of said cable being secured to one of the elevators and the other reach thereof to the other elevator, a supporting arm keyed to said driven shaft adjacent each drum and extended therefrom to near the inner ends of said lugs, a spring actuated clutch arm pivotally mounted on said supporting arm and having a lug engaging arm extended from its pivot and adapted for engagement with a lug on the drum, a gravity actuated safety dog pivotally mounted to engage the peripheral rack of each drum, a lever fulcrumed on the upper portion of said upright frame work near each corner thereof, a cable connecting the front end of each

lever to each of said clutch arms, and another cable connecting the front end of each lever to one of said dogs. 40

4. An apparatus of the class described including in combination an upright frame-work providing a vertical guide-way, a cage in said guide-way for vertical movement, means to raise and lower said cage, a lever 45 fulcrumed on said frame-work and having an extension projecting from its fulcrumed portion, a spring connected at one of its ends to the outer portion of said extension and at its other end to a fixed point opposed with respect to said lever to the extension thereon, said spring being so located with respect to the lever fulcrum that when the lever is tilted in either direction, it will be held in such position by said spring. 50 55

5. An apparatus of the class described including in combination an upright frame-work providing a vertical guide-way, a cage in said guide-way for vertical movement, means to raise and lower said cage, a lever fulcrumed on said frame-work and having an extension projecting from its fulcrumed portion, a spring connected at one of its ends to the outer portion of said extension and at its other end to a fixed point opposed with respect to said lever to the extension thereon, said spring being so located with respect to the lever fulcrum that when the lever is tilted in either direction, it will be held in such position by said spring, and 60 means on the upper portion of the cage for contact with the lever on one side of its fulcrum. 65 70

CARL ZETTERLUND.
